UNITED STATES PATENT OFFICE.

FRED J. MILLER, OF SILVER CITY, IOWA.

SELF-SOAPING WASHBOARD.

1,247,561.

Specification of Letters Patent.

Patented Nov. 20, 1917.

Application filed May 23, 1917. Serial No. 170,439.

To all whom it may concern:

Be it known that I, FRED J. MILLER, a citizen of the United States, residing at Silver City, in the county of Mills and State of Iowa, have invented certain useful Improvements in Self-Soaping Washboards, of which the following is a specification, reference being had therein to the accompanying drawing.

10 The invention relates to a washboard and more particularly to the class of self soaping washboards.

The primary object of the invention is the provision of a board of this character where- 15 in a bar or cake of soap is held in a manner so that the rubbing surface of said board can be supplied with a quantity thereof when the occasion requires for the soaping of clothes to assure the thorough cleaning 20 of the same.

Another object of the invention is the provision of a washboard of this character wherein the soap is confined in a frame which is slidably fitted in the board so that 25 on movement of the frame the soap therein will be scraped from the cake and delivered on to the rubbing surface of said board for the application to the clothes in the rubbing 30 of the same.

30 A further object of the invention is the provision of a washboard of this character wherein the construction thereof is novel in form to assure the easy soaping of the rubbing surface of the board without undue exertion on the part of the user of said board.

A still further object of the invention is the provision of a board of this character which is extremely simple in construction, thoroughly reliable and efficient in operation, strong, durable and inexpensive in 40 manufacture.

With these and other objects in view the invention consists in the features of construction, combination and arrangement of 45 parts as will be hereinafter fully described, illustrated in the accompanying drawing and pointed out in the claims hereunto appended.

In the accompanying drawings:

50 Figure 1 is a rear elevation of a washboard constructed in accordance with the invention;

Fig. 2 is a front elevation thereof;

Fig. 3 is an enlarged sectional view on the 55 line 3—3 of Fig. 1;

Fig. 4 is a sectional view on the line 4—4 of Fig. 1; and

Fig. 5 is a sectional view on the line 5—5 of Fig. 1.

Similar reference characters indicate corresponding parts throughout the several views in the drawings.

Referring to the drawing in detail, A designates the body of the washboard which includes the side rails 10, upper and lower 60 cross rails 11 and 12, respectively, spaced parallel longitudinally disposed braces 13, breast board 14 and corrugated rubbing section 15, which latter is secured in the rails 10, 11 and 12 in the usual well known manner. 70

Arranged at the head of the body A is a pusher bar 16 which is provided with guide arms 17 arranged at the rear side of the breast board and formed with ribs 18 slidably engaged in suitable grooves or channels provided in the inner faces of the side rails 10 of said body, while centrally of said pusher bar 16 is a plunger bar 19 which works through a suitable hole in the upper 80 cross rail 11 and is connected with a soap container hereinafter described. 75

The soap container is in the form of a substantially rectangular shaped frame 20 open at its front and back and slidably 85 fitted between the braces 13, the frame 20 being designed to receive a cake or bar of soap 21 which acts directly upon the rubbing section 15, the latter being provided with a plurality of holes 22 in the path of 90 movement of the cake or bar of soap 21, the edges of these holes 22 being designed to serve as scrapers adapted to cut the bar or cake of soap so that the disintegrated quantity will pass through the holes to the outer 95 surface of the rubbing section 15 when the container is reciprocatingly moved at the rear thereof for the application of the soap to clothes when rubbed upon said section, thereby thoroughly soaping the same for 100 the thorough cleaning of the clothes in the use of the washboard.

Surrounding the plunger rod 19 is a coiled compression spring 23 which has one end bearing upon the upper rail 11 and the other 105 end against a fixed washer 24 of the plunger rod 19 so that said plunger rod and pusher bar are resiliently supported or tensioned whereby on manually depressing the pusher bar 16 the soap container will be 110

removed in one direction against the resistance of the spring 23 which automatically moves the soap container in the reverse direction when the pressure is released from the pusher bar and in this manner the soap is automatically fed to the rubbing surface of the washboard.

Removably engaged in the rear side of the soap container and bearing against the soap

10 bar or cake 21 therein is a follower in the form of a plate 24 which is carried upon a resilient arm 25 swingingly supported upon the plunger rod 19, the rod being fitted with a bolt 26 on which is engaged the resilient 15 arm 25 and threaded on this bolt 26 is a wing binding nut 27 which holds the resilient arm in adjusted position thereon as shown by dotted lines in Fig. 1 or by full lines in Figs. 1, 2 and 3 of the drawing.

20 When the follower plate 24 has been shifted away from the soap container a cake or bar of soap can be readily removed therefrom or placed therein as the occasion may require.

25 Slidably connected with the braces 13 is a closure plate 28 which is adapted to move in a position for closing the back of the soap container as shown in Fig. 1 of the drawings and on movement of said plate 28 30 in the reverse direction free access can be had to the container.

In the use of the washboard when it is desired to supply a quantity of soap to the rubbing face of the rubbing section 15 of 35 said board the user depresses the pusher bar 16 against the resistance of the spring 23 which moves the soap container in one direction and the bar or cake of soap therein is sustained against the inner face of the 40 rubbing section by the follower so that on the movement of the container the soap is fed through the holes in the rubbing section on to the rubbing surface thereof. On retrograde or reverse movement of the container which is affected under the action 45 of the spring 23 when pressure is relieved from the pusher bar 16 the feeding of the soap is repeated or a further quantity of said soap is delivered on to the rubbing

surface of the rubbing section of the board 50 so that on the rubbing of clothes thereon the soap will be supplied thereto for the thorough cleaning of the clothes.

From the foregoing it is thought that the construction and manner of operation of 55 the device will be clearly understood and therefore a more extended explanation has been omitted.

What is claimed is:

1. A washboard comprising a body having 60 a rubbing section provided with holes in a portion thereof, a soap container slidably mounted at the rear of the section and movable over the apertured portion, a pusher bar at the head of said body and connected to said container for moving the same, and means for resiliently supporting the pusher bar.

2. A washboard comprising a body having 70 a rubbing section provided with holes in a portion thereof, a soap container slidably mounted at the rear of the section and movable over the apertured portion, a pusher bar at the head of said body and connected to said container for moving the 75 same, means for resiliently supporting the pusher bar, and a follower for the container to press a bar or cake of soap therein against the apertured portion of the section for the feeding of the soap on to the rubbing surface of said section.

3. A washboard comprising a body having 80 a rubbing section provided with apertures, braces at the rear of the rubbing section, a frame forming a soap container slidably fitted between the braces, a pusher bar 85 slidably supported at the head of said body, a plunger connected with the bar and frame for moving the same on depressing the pusher bar, means for tensioning the pusher bar and plunger and a resiliently and swingingly supported follower working within the container for pressing soap in the latter through the apertures in the rubbing section on reciprocatingly moving the container.

In testimony whereof I affix my signature.
FRED J. MILLER.
